Primary Examiner—Raphael Barkai*Assistant Examiner*—Randall H. Gholson(74) *Attorney, Agent, or Firm*—Myers & Kaplan, LLC; Joel D. Myers; George P. Bonanto(57) **CLAIM**

The ornamental design for an adjustable ratchet wrench, as shown and described.

DESCRIPTION

FIG. 1 is a top view of a first embodiment of an adjustable ratchet wrench showing my new design:

FIG. 2 is a side view thereof:

FIG. 3 is a bottom view thereof:

FIG. 4 is a side view thereof:

FIG. 5 is a front view thereof:

FIG. 6 is a rear view thereof:

FIG. 7 is a top view of a second embodiment of an adjustable ratchet wrench showing my new design:

FIG. 8 is a side view thereof:

FIG. 9 is a front view thereof; and,

FIG. 10 is a rear view thereof.
